MEDICAL OSCILLATOR

Albert Tonkin, St. Paul, Minn., assignor of one-half to M. Sidney Hedeon, St. Paul, Minn.

Application August 7, 1950, Serial No. 178,087

3 Claims. (Cl. 128—64)

1

This invention relates to medical oscillators and particularly to a portable apparatus, that is adapted to safely provide massage and manipulative treatments, that are beneficial in accelerating peripheral and deep circulation as well as carefully and gently putting skeletal joints through their normal range of motion.

It is apparent that there is need for apparatus, which will stimulate peripheral circulation, and at the same time, loosen up muscles and joints. Such apparatus must be adaptable to treat the back and parts of the torso, as well as the limbs. It must be portable, so that it may readily be brought where needed. It must be moderate in its treatment, so that it may be safely used under all circumstances. For example, in the treatment of poliomyelitis, requiring a great amount of gentle hand massaging, there is need for a safe device, to provide treatment for a greater number of cases, with a limited hospital staff. The apparatus must include means for warming the affected parts, as required, and so arranged that the patient is not contacted by any cold apparatus, even at the beginning of the treatment.

An important object of my invention is to provide an apparatus, that will concurrently or singly act to accelerate peripheral circulation and to restore function of paralyzed and inactive muscles and other members of the body. The apparatus must have elements for either purpose, which can be arranged if needed, to treat a considerable area and applied to either limbs or torso, by encircling same or by parts of the body reposing thereon.

Another important object is to provide such an apparatus, with a device for warming the air or fluid within the elements, to raise the sub-normal temperature, that is prevalent in the diseased parts. Such device must be closely controllable as to degree of warmth, with an on and off arrangement, and provision made for heating at the source, with means for exhausting to atmosphere, to quickly attain a comfortable temperature for the patient.

Another important object is to provide such an apparatus, having alternating action in adjacent or otherwise arranged elements, and adapted to operate on different sets of elements, the oscillations of all of which are subject to fine control, as to frequency and duration of the respective steps.

Another important object is to provide such an apparatus, in portable as well as stationary form, so that it may easily be brought where needed,

2

and so it may be used to treat more than one patient at a time, by attaching additional elements.

Another important object is to provide such an apparatus, affording gentle and moderate massage and manipulative treatments, that are safe under all circumstances, without subjecting the body to alternate suction and pressure, without rubbing and chafing or other drawing and working of the limbs.

Another object is to provide an apparatus with such desirable features, but which can be produced at a reasonable price, so it may be in general use.

Other objects will be apparent from the description and appended claims.

For a full disclosure of my invention, reference is made to the description following and to the drawings, in which—

Fig. 1 is a side elevation view of the apparatus in operative position, with such parts thereof in section as necessary to show the pump and its operating mechanism.

Fig. 2 is a front elevation view of the apparatus, with a part thereof in section as necessary to show the electric heater.

Fig. 3 is a rear elevation view of the apparatus.

Fig. 4 is a plan view of the apparatus.

Fig. 5 is a plan view of an inflatable treating element, consisting of a multiple arrangement of small tubes.

Fig. 6 is a plan view of another type of inflatable treating element, consisting of a large tube, of which several may be joined to a header.

Fig. 7 is a cross sectional view taken on line 7—7 of Fig. 5, showing alternate tubes of the multiple small tube arrangement inflated.

Fig. 8 is a cross sectional view taken on line 8—8 of Fig. 6, showing the large tube element inflated.

Fig. 9 is a view similar to Fig. 8 but with the large tube element deflated.

Referring now to the several figures of the drawing, the reference character 10 indicates a piston, secured to a piston rod 11, at substantially the mid point thereof. This piston rod is provided with a conventional sealing ring 12 and a conventional bearing 13, in the cylinder cap 14 and likewise in the end of the cylinder 15. The cylinder is preferably of cast iron and the cap of cast aluminum, secured to the cylinder in conventional manner with machine screws. Grooves are provided in the cap and in the end of the cylinder, for the sealing rings, and similarly recesses machined for the bearings. It will

be observed that a double acting pump is provided. A heater compartment is provided around the cylinder, by means of an outer shell 16, and a layer of insulation 17 placed between said outer shell 16 and an inner shell 18. An electric heating element 19, of suitable capacity, is mounted on the cylinder within the compartment, and subjected to control in conventional manner. The heater compartment is joined and is secured to the cylinder, by machine screws or in other accepted manner. Each end of the cylinder is provided with three ports 21, into which are inserted threaded bushings 22. These are preferably positioned, so that connection can be made, on each side and the front at the top and bottom of the cylinder, for a purpose to be subsequently explained.

The lower end 23 of the cylinder is preferably cast integral with the housing, and a gasket 24 is provided in the juncture between the cylinder and housing. A connecting rod 25, with a bearing 26, is joined to the piston rod 11, by a pivot pin 27. The other end of the connecting rod is similarly provided with a bearing 28 and a pivot pin 29, by which it is joined to an eccentric plate 30. The eccentric plate is secured, by means of a drive pin 31, to a shaft 32. This shaft has conventional bearings 33 at each end thereof. A sleeve 36 of rubber or other material, having frictional grip, is engaged by a friction disc 37. A shifting lever 38, secured by a pivot 39 and engaging a groove 40 in the spool 35, provides for different positions and speeds of the friction spool, with respect to the friction disc. The friction disc 37 is secured, by means of a drive pin 41, to a reduction shaft 42. A drive shaft 43 is positioned for pairing of gears with said reduction shaft. Both shafts are provided with conventional bearings 44 at each end. A gear 45 is fixed on the drive shaft, which meshed with a gear 46 on the reduction shaft, provides for low speed operation. Similarly a gear 47 fixed on the drive shaft and meshed with a gear 48 on the reduction shaft, provides for high speed operation. The gears 45 and 47 are fixed on the drive shaft by set screws or equivalent means. The gears 46 and 48 are retained longitudinally in a free running position on the reduction shaft, by conventional snap rings engaging grooves in the shaft. These two gears are provided with sockets, for engagement by the pins of a clutch 49, for low and high speed respectively. This clutch is subject to movement longitudinally on the reduction shaft, into engagement with either gear or into a neutral position, by means of a shifting lever 50 on a pivot 51. The clutch has threaded pins engaging grooves in the reduction shaft, in a conventional manner, for transmitting torque to the reduction shaft and the friction disc 37. A bracket 52 provides for attachment of a universal type driving motor 53. The control of speed provided by the clutch and gearing and, settings of friction disc and spool, provides for any desired variation to meet the needs. To enclose and provide support for the mechanism above described, a housing is provided. This consists of a main housing 55, an upper end plate 56 and a lower end plate 57. These are secured together with conventional machine screws and studs, and as previously stated, the top of the housing forms the lower end of the cylinder. The housing is secured, by means of plates 58 and 59 and machine screws 60, to a handle 61. This handle is bifurcated at the bottom, accommodating an axle 62, with a pair of wheels 63, toward the

rear, and a prop 64, at the front. The wheels are preferably provided with pneumatic tires and the prop with a rubber cup. It will be noted from the drawings, that the apparatus is thus rendered very portable, but at the same time, is very stable. A hook 65 is provided at the top of the handle, to accommodate a conventional extension cord. An electric terminal 66 is provided, and by conventional wiring, circuits formed for motor 53, and heating element 19. Inserted in these circuits, are toggle switches 67 for motor and for heater and pilot lights 68 respectively for the switches. A monometer 69, with a scale, is provided for connection with tubes to the device, to cut in and determine at a glance the pressure existing in the system. Panels 70, which are easily removable, provide access to the electrical terminal and for adjusting piston stroke respectively.

Inflatable treating elements are of two types, as disclosed respectively by Fig. 5 and Fig. 6. These are connected, by appropriate tubes, to the respective ports 21, of the cylinder 15. These tubes may be provided with means for engaging the threaded bushings 22. The element, covered by Fig. 5, consists of a substantially rectangular mat, in which, sectional strips 71 are formed into closed end units and having connection to headers 72, at the respective ends of the mat. Dams 73 are provided, to separate the respective headers and units, and bleeder valves 74 provide for expulsion of cold air from each respectively. Tubes 75 join same respectively to the ports 21 in each end of the cylinder. By application of fluid pressure, in oscillating form and of opposite phase, to the respective headers, the mat assumes a cross-section, as disclosed by Fig. 7, and alternating with respect to the tubes. The element 76, covered by Fig. 6, acts similarly to one of the sectional strips 71, but is of substantial size and is preferably provided separately, and individually joined to respective headers, by a tube 77. Also, each is provided with a bleeder valve 78. Like the element of Fig. 5, there may be alternate action in adjoining tubes, or any prescribed intermeshing arrangement can be provided. Also, these elements are not confined to a parallel arrangement, as some elements may be arranged at an angle to each other, if desired. Figs. 8 and 9 respectively show a cross section of two of these large elements, one being inflated and the other deflated. The form shown has heavy material for one half or base portion 79 of it, so that the tendency is to inflate only upward in the form of a semi-circle. By applying the element of Fig. 5, for example, around a limb, peripheral circulation of blood and lymph is accelerated. At the same time, an arrangement of elements, as shown in Fig. 6, may be applied to raise and lower the limb appreciably, to restore mobilization of muscles and normal flexing of the joint, by the mild exercise. Besides tending to make inactive members active, the motion of itself improves circulation, and greatly aided by improved peripheral circulation, induced by the element of Fig. 5, still greater activity is attained, by reason of the improved circulation. Both types of elements can concurrently be applied to limbs or torso, by encircling or by parts of the body reposing thereon. By use of the bleeder valves, all cold air is quickly expelled, permitting influx of air into the elements, which has been warmed to the degree desired. This closely controlled warmth is very helpful, to restoration of circulation and

activity in members of the body. Although the results of the action of the two types of elements in combination, has been much sought after, the elements may be applied independently. The element of Fig. 6, applied in prescribed numbers and arrangement, will have wide and important use in manipulating spinal joints safely and comfortably, and aided by the application of controlled warmth. It is in this manner particularly favorable for reducing pressure on swollen nerves, that emerge from the spine. As previously referred to, several of each of the two types of elements may be joined to tubes or headers, connected to the ports at the two ends of the cylinder, in the desired arrangement of numbers and with respect to the alternating phases of action. The coordinating action of the two types of elements, and a substitute for tedious hand treatments, unlimited as to time and number of patients, is very important. The treatment is uniform at all times, in accordance with prescribed setting of the apparatus, and unlike hand treatments, which will vary considerably, even when administered by the same person, let alone different persons.

From the above, it is apparent how my medical oscillator is constructed and that it meets a great need. It is moderate in its action and safe under all circumstances. It increases circulation, and with the same treatment at the same time, can be made to stimulate and restore function of weakened muscles, which may be temporarily paralyzed, and restore normal motion of stiffened joints. Massaging and manipulation elements are easily adjusted to act on all parts of the body, by wrapping around the limbs and the body, or the limbs or body reposing on the elements. Elements, of sizes and numbers to suit, are provided, to meet all requirements. The air or fluid in the elements is subjected to closely controllable warmth, at its source of entry, instead of warming the body or limb in a housing or by a deflector. The entire apparatus is portable and readily brought where needed, and may be used to treat more than one patient at a time, by attaching additional elements. With connections made at opposite ends of the cylinder, alternate actions are produced in adjacent elements. It is adjustable to frequency and duration of the respective steps. By the use of the elements, with the narrow alternate acting strips, wrapped around a limb, around the body, or in some cases, the limb or a portion of the body reposing on said element, the gentle rhythmic pulsations accelerate circulation of blood and lymph. By reason of the more active and healthy peripheral blood circulation, which nourishes the nerve termini, the function of these termini is improved. Many cases of nervousness and attendant irritability are merely cases of reduced peripheral circulation. Vascular diseases today are a leading cause of disability and discomfort, the elimination of which would add years to the average life. The lack of blood to the extremities of the body causes numbness, coldness and rheumatic pains. With improvement in circulation, diabetic ulcers and gangrenous conditions can be arrested, avoiding amputation. Frost bitten parts can likewise be restored. Arterio-sclerosis and other stubborn ailments can be greatly alleviated. By the use of the larger single elements, placed singly or in multiple and alternately acting or otherwise arranged, on which the limb or body is placed, muscle tissue is massaged, circulation is accelerated and absorbing any ab-

normal deposits in the tissues. This treatment may be applied separately, as passive exercise, or concurrently with the treatment for accelerating circulation, as appears very beneficial in the treatment of poliomyelitis. Both kinds of treatment are further made more effective, by the warming action of the apparatus, to raise the subnormal temperature, which is commonly prevalent in many diseased parts. The warming action, which is provided by heating the air at its source, before it enters the treating elements, is closely controllable and may be turned on and off. This apparatus is therefore vital in the treatment of diseases, in which body fluid circulation is lacking, and any disorders of the vascular, muscular and nervous systems. It is also vital in re-establishment of joint motion including flexion and extension of spinal joints. It provides safe, comfortable treatment, without strain, under all circumstances. Pain is relieved and warmth returns to the tissues. Indications are that it is even beneficial in the case of sinus infection. This, as well as treatment of pneumonia, may be because of spinal joint extension, as accomplished by the large tube treating elements. This tends to normalize sympathetic nerve function, which in turn, normalizes blood flow to all parts. There is also a raising and lowering of the ribs, which increases and decreases the volume of the chest cage. The resulting alternating positive and negative pressures, within the chest cavity, accelerates the blood flow in the large veins of the chest, which gather the blood from all parts of the body and return it to the heart. By application of the large tube treating elements to the back with warmth and rhythmic pressure, the back muscles relax and the front parts of the vertebrae are separated from one another, within anatomical limits. This extension of the vertebral column stretches spinal ligaments and tissues, causing increased drainage of fluids of the spinal tissues including the spinal cord. Proper drainage of the spinal cord is very important in the treatment of such diseases as anterior poliomyelitis. Increased circulation of the spinal tissues also tends to prevent, and eliminate, if present, arthritis of the spine. The large tube treating elements can be placed under a patient's abdomen, with the patient face down, and with the machine properly adjusted for frequency and pressure, intestinal function is improved. As previously stated, the small tube treating elements particularly accelerate peripheral circulation and this applies to the lymph as well as the blood. Motion of both is necessary for the proper nutrition of a part. The heat, which is also supplied by the element, causes the area to be flooded with blood. Blood is the greatest healing factor the body has. In the case of a nervous or mentally ill patient, a small tube treating element, placed flat under the patient's back and properly regulated as to pressure and temperature, will, by the gentle soothing massage and heat, provide helpful relaxation. The value of the two types of treating elements acting concurrently, is definitely very great, in the treatment of many disorders and particularly poliomyelitis.

Although the above description is somewhat lacking the long and difficult words of medical science, or the scientific explanation for the results, the treatment, herein referred to, has long and generally been accepted as beneficial in the treatment of many diseases. It has been

necessary heretofore, however, to administer the treatment by tedious hand massaging, supplemented by apparatus, with considerable limitations as to its safe and moderate action, and consequently could not be extended to use on a large scale. It is apparatus, that may be used safely on a large scale, for concurrently treating disorders of circulation and inactive muscles and joints, that is needed the most.

While I have shown and described a preferred form of my invention, it is obvious that many changes, which are within the scope of my invention, will be apparent to those skilled in the art. I therefore desire to be limited only by the scope of the appended claims.

What I claim is:

1. An apparatus of the class described comprising a double acting pump, adapted to give puff or suction strokes at respective ends thereof, operating means for said pump, a variable driving connection between said operating means and said pump, a clutch for releasing said operating means, conduits connected at respective ends of said pump, inflatable treating elements, each unit thereof consisting of an elongated tube with one end closed and the other end provided with a connection to a conduit, said conduits being branched to accommodate a plurality of inflatable treating elements in prescribed arrangement of numbers and sizes, said inflatable elements being flexible and adapted to be wrapped around to encircle a limb or portion of the body or such limb or portion reposed on said elements and subjected to alternating rhythmic pulsations of said elements according to arrangement of number and size of elements connected to respective ends of said pump, whereby by reason of such alternating rhythmic action of said inflatable elements an acceleration to circulation and massage of muscles and articulation of joints is provided at the same time.

2. An apparatus as claimed in claim 1, characterized by an inflatable treating element substantially rectangular in shape with headers at each end distributing fluid pressure to respective

5 sectional tubular strips of said element, said sectional strips being closed at ends opposite to said headers and having a prescribed arrangement of numbers attached to the respective 10 headers, said fluid pressure being supplied to said treating element in oscillating form and of opposite phase in the respective headers, bleeder valves adapted to be opened for expulsion of cold fluid from portions of element joined to respective headers permitting rapid influx of heated fluid into said element, said element being adapted to be wrapped around to encircle a limb or portion of the body or such limb or portion reposed on said element for said element to react against same, whereby by reason of alternating action in adjacent or otherwise arranged strips a stimulus to circulation and to the mobilization of muscles and joints is provided.

15 3. An apparatus as claimed in claim 1, characterized by inflatable treating elements provided with individual bleeder valves, said elements being of substantial size and individually joined to a conduit, so as to be freely subject to any intermeshing arrangement and particularly adapted to be wound around body or limb and freely arranged in various positions, whereby said elements will be particularly adaptable in normalizing muscle function and skeletal joint motion, and may be used at the same time with 20 smaller elements in multiple, which are principally acting to accelerate circulation.

ALBERT TONKIN.
